CLAIM

The ornamental design for an elastic cord lock upper member, as shown and described.

DESCRIPTION

FIG. 1 is a top plan view of an elastic cord lock upper member showing my new design;

FIG. 2 is a front elevational view thereof, which is identical to the rear view;

FIG. 3 is a right side elevational view thereof, which is identical to the left side elevational view;

FIG. 4 is a bottom plan view thereof; and,

FIG. 5 is a perspective view thereof.
